CLAIM

We claim the ornamental design for a reservoir for dental appliance, as shown and described.

DESCRIPTION

FIG. 1 is a perspective view of a reservoir for dental appliance showing our new design;
FIG. 2 is a front elevation view thereof;
FIG. 3 is a rear elevation view thereof;
FIG. 4 is a side elevation view thereof;
FIG. 5 is a side elevation view of the opposite side of the design as that shown in FIG. 4;
FIG. 6 is a top plan view thereof;
FIG. 7 is a perspective view of another embodiment of a reservoir for dental appliance showing our new design;
FIG. 8 is a front elevation view thereof;
FIG. 9 is a rear elevation view thereof;
FIG. 10 is a side elevation view thereof;
FIG. 11 is a side elevation view of the opposite side of the design as that shown in FIG. 10; and,
FIG. 12 is a top plan view thereof.

The broken lines shown in the drawings illustrate portions of a reservoir for dental appliance that form no part of the claimed design.
